DESIGN FOR A DISPLAY STAND

Wilbur D. Canaday, Stamford, Conn., and Enoch Norris Brown, Brockton, Mass., assignors to Lenthalic Incorporated, New York, N. Y., a corporation of New York

Application December 6, 1934, Serial No. 54,316

Term of patent 3½ years

To all whom it may concern:

Be it known that we, Wilbur D. Canaday and Enoch Norris Brown, citizens of the United States, respectively residing at Stamford, in the county of Fairfield and State of Connecticut, and Brockton, in the county of Plymouth and State of Massachusetts, have invented a new, original, and ornamental Design for a Display Stand, of which the following is a specification, reference being had to the accompanying drawing, forming part thereof.

In the drawing, the figure is a perspective view of a display stand showing our new design.

We claim:

The ornamental design for a display stand substantially as shown.

In witness whereof we affix our signatures.

WILBUR D. CANADAY.
ENOCH NORRIS BROWN.
